SEWING MACHINE

Fred Ashworth, Wenham, Mass., assignor to
United Shoe Machinery Corporation, Paterson,
N. J., a corporation of New Jersey

Original applications March 1, 1932, Serial No.
596,051, and November 23, 1933, Serial No.
699,341. Divided and this application October
9, 1934, Serial No. 747,536

9 Claims. (Cl. 112—46)

The present invention relates to shoe machines and is herein disclosed as embodied in a machine adapted for use in the manufacture of stitchdown shoes to stitch the welt to the out-turned upper and outsole of a shoe.

The present application is a division of the applicant's copending application Serial No. 596,051, filed March 1, 1932, and also contains divisional subject-matter from applicant's copending application Serial No. 699,341, filed November 23, 1933.

The principal object of the invention is to provide a novel and improved welt cutting mechanism in a welt attaching machine of this or similar character for operating on a shoe provided with a welt running completely around the shoe which will act instantaneously when tripped into operation to sever the welt and thus permit an accurate determination of the position of the cut to form a joint with the leading end of the attached welt at the conclusion of the welt attaching operation.

It is another object of the present invention to provide novel and improved means for enabling the operator accurately to measure the amount of new welt passed through the welt guide to provide a sufficient length of welt for the beginning of a new sewing operation.

With these and other objects in view, as will hereinafter appear, a principal feature of the invention consists in the provision with a spring actuated knife of a toggle connection which is arranged when tripped to permit the knife to be moved downwardly instantaneously under the pressure of its spring and sever the welt.

Another feature of the invention consists in the provision of a novel and improved trip mechanism including a feeler which is actuated by engagement with the leading end of the attached welt to actuate the knife and is constructed and arranged to be positioned automatically with relation to the other parts of the shoe during the transfer of the operation around the shoe sole to prevent any possibility that the finger will be tripped prematurely to sever the welt.

The several features of the present invention consist also in the combinations and arrangements of parts hereinafter described and claimed which, together with the advantages to be obtained thereby will be readily understood by one skilled in the art from the following description taken in connection with the accompanying drawings in which Fig. 1 is a view in front elevation of the machine head; Fig. 2 is a detail view in right side elevation on an enlarged scale

of the welt cutting device; Fig. 3 is a view similar to Fig. 2 with one fork of the knife actuating lever and the toggle release broken away to show underlying parts; Fig. 4 is a plan view of the knife actuating lever and the latch for holding the knife in inoperative position shown in Figs. 2 and 3; Fig. 5 is a view in front elevation of the welt cutting device with the feeler withdrawn from the work; Fig. 6 is a view similar to Fig. 5 with the feeler depressed into operative engagement with the work; Fig. 7 shows the operation of the cutting device to sever the welt upon engagement of the feeler with the leading end of the welt; Fig. 8 is a detail view partly in section of the feeler member for actuating the welt cutting mechanism and the slide on which it is mounted; Fig. 9 is a sectional view taken on the line 9—9 of Fig. 8; Fig. 10 is a detail perspective view on an enlarged scale of the sliding support for the feeler member shown in Figs. 8 and 9; Figs. 11 to 15 inclusive illustrate a modified form of welt guiding and cutting mechanism in which the automatic trip mechanism controlled by the advance of the shoe has been removed, and manually operable control devices substituted, Fig. 11 being a detail view in right side elevation of the cutter and toggle support, Fig. 12 being a plan view of the parts shown in Fig. 11, Fig. 13 being a detail view in front elevation of the cutter and toggle support with the toggle in straightened position, Fig. 14 being a view similar to Fig. 13 with the toggle broken to sever the welt, and Fig. 15 being a detail view partly in section of the welt guide to illustrate the welt measuring device.

As has been stated, the present invention is disclosed in the drawings as embodied in a sewing machine adapted to stitch the welt to the out-turned upper and sole of a stitchdown shoe supported upon a last. In the machine shown, the operating parts including the needle and awl, a looper, a thread finger and a shuttle are so arranged that the work is fed to the machine in an upright position, the construction and operation of these parts and other parts of the machine not hereinafter specifically described being the same as the corresponding parts of the machine disclosed in applicant's copending application Serial No. 596,051.

The welt guiding and cutting mechanism which forms more specifically the subject-matter of the present invention, is similar in many respects to that disclosed in the applicant's Patent No. 1,774,498, dated September 2, 1930. The presser foot is generally indicated at 16 in Fig. 55.

1 formed on a curved member 18 which is supported at its ends on the upwardly extending arms of a forked presser foot bar 20. The welt cutting mechanism is supported integrally with 5 the presser foot mechanism of the machine, and comprises a cutter member 50 which is mounted to slide in a slot 52 in a bracket 54 formed integrally with the member 18 which carries the presser foot 16. The cutter member 50 is arranged 10 to intersect a guideway 57 formed on the under side of the member 18 through which the welt strip is fed at an angle to form a bevelled end to the welt. A cover plate 61 screwed to the bracket 54 serves to close the slot 52 and the lower end of the guideway 57 to hold these elements in position. At its upper end the cutter member 50 is connected to one arm 63 of a bifurcated cutter actuating lever 62 secured to a short rock shaft 64 which is journaled in a bearing 20 formed in the right hand fork of the presser foot bar 20 as viewed from the front of the machine. A heavy spring 67 coiled about the bearing for the rock shaft 64 and engaging at one end with a pin on the lever 62, tends at all times to depress the lever 62 and cutter member 50 to sever the welt. As in the applicant's patent above referred to, the lever 62 is held in a raised position normally during the operation of the machine through mechanism which is arranged to 25 engage with the second arm 63 of the bifurcated lever 62 to prop the lever and cutter member 50 in raised position, and is arranged when rendered operative to permit the lever 62 and knife 56 to fall under the pressure of the spring 67 30 and sever the welt.

In accordance with one feature of the present invention, a novel and improved mechanism is disclosed for holding the lever 62 in its raised position which may be instantaneously and 40 easily tripped to sever the welt and will at the same time provide a safe and sure support for the lever 62 and knife during the transfer of the operation about the shoe. The supporting mechanism referred to comprises a toggle lever 45 which consists of a link 72 punched to receive the tapered end of the arm 63, and a link 74 pivotally connected to the link 72, and at its lower end to the presser foot bar 20. The toggle links 72 and 74 are normally held in a straightened 50 position as shown in Fig. 6, with surfaces 76 formed respectively on the toggle links 72 and 74 in engagement by means of a small spring 78 connected at one end to the presser foot bar 20, and at its other end to the toggle link 74.

55 In a preferred form of the present construction, an automatically acting trip mechanism is provided comprising a feeler member 70 which is arranged for engagement with the leading end of the attached welt on the shoe to break the 60 toggle connection and sever the welt at a point which will cause the two ends of the welt to fit together in a smooth appearing joint. The feeler member 70 is pivotally secured to a vertically movable slide 80, and is provided at its upper 65 end with a laterally offset butt 82 which is arranged in the depressed or operative position of the feeler member 70 to contact with the upper end of the toggle link 72, so that the movement of the feeler member 70 about its pivot upon engagement with the leading end of the welt, will 70 cause the butt 82 to engage with and rotate the toggle link 72 to break the toggle and permit the lever 62 and cutter member 50 to descend under the pressure of the spring 67 to sever the welt. The feeler member 70 is normally held in

a vertical position out of contact with the toggle member 72 in engagement with a pin 86 on the slide 80 by means of a small spring 84. The slide 80 may be locked in raised or inoperative position during the normal operation of the machine 5 to prevent an accidental operation of the welt cutter, by engagement of a latch 88 pivotally mounted on the arm 63 of the cutter actuating lever 62 with a projecting nub 90 on the upper end of the slide 80, and is released by the operator to permit the slide 80 and the feeler 70 to be depressed into operative position toward the end of the sewing operation, by means of a laterally extending manually operable lever arm 92 formed on the hub of the latch 88. 15

With the present construction, the feeler member 70 for automatically tripping the welt cutter, is constructed and arranged to permit an automatic adjustment of the feeler member vertically in accordance with variations in the thickness of the shoe sole, and laterally to conform to the contours of the shoe upper, to eliminate the possibility that the finger will be actuated prematurely by contact with some part of the shoe to cut the welt. In order to secure a sensitive vertical adjustment of the feeler member 70 in accordance with the thickness of the shoe sole, the slide 80 is mounted to move relatively to a second slide 94 which is in turn mounted for vertical movement on a supporting bracket 96 formed on the forked portion of the presser foot bar 20. The slide 80 is cut away on its rear side to receive the slide 94, and is provided with a downwardly extending tongue 98 which engages with a corresponding track 30 formed in the rear side of the slide 94. The slide 94 is also grooved to receive two laterally extending trunnions or bars 100 which engage with corresponding slots 102 in the bracket 96. A light spring 104 seated in a recess 106 in the bracket 40 96 and engaging at its lower end with a pin 108 on the tongue 98, tends to move the slide downwardly to hold the feeler member 70 in yielding contact with the work. In order to secure an automatic lateral adjustment of the feeler member 45 to conform to the contours of the shoe upper, the lower end of the feeler member is formed as a separate member 110 which is hinged at 112 on a bracket 113 on the member 70 to move rearwardly away from the shoe, and is normally held 50 in a straightened position by a small compression spring 114 inserted between the lower end of the slide 80 and the hinged member 110. The work engaging parts 110 of the feeler member 70 is also adjustable longitudinally in the line of 55 feed to permit a close adjustment of the timing in the operation of the cutting knife with relation to the leading end of the welt, so that a tight joint may be formed between the two ends of the welt. To this end the bracket 113 is 60 mounted to swing in the line of feed about the pivot 115 on which the feeler member 70 is mounted to turn, and is held adjustably in position by means of a clamping screw 117 which extends through a transverse slot 119 in the member 70, and is threaded into the bracket 113. 65

The cutter actuating lever 62 is automatically raised upon starting the machine to raise the cutter knife 50 out of the path of the welt, and to reset the toggle links in straightened position by 70 means of a lever 116 which is pivoted at 118 on the machine frame, and has formed on an upwardly extending arm thereof an engaging surface 120 adapted for contact with a downwardly extending arm 122 secured to one end of the rock 75

shaft 64. The lever 116 is rocked in the starting of the machine to cause the surface 120 to engage with and rock the arm 122 and shaft 64 to move the lever arm 62 and cutter 50 to their raised position where they are held by the locking of the toggle links 72 and 74. For the details of the operation of this mechanism for resetting the toggle, reference may be had to the applicant's pending application Serial No. 596,051 above referred to.

The trip mechanism herein disclosed for holding the lever 62 and welt knife 50 in a raised position and for tripping these parts to instantaneously sever the welt, is also well adapted for

15 manual operation to enable the operator to sever the welt at the exact point desired during the continued operation of the machine. A modified form of the present structure to provide a manually operable trip mechanism, is illustrated in

20 Figs. 11 to 15 inclusive of the drawings, the parts illustrated being substantially those previously described with the feeler mechanism removed and a manually operable trip lever substituted therefor. In Figs. 11 and 12 the cutter member 50 is

25 mounted to slide in a guideway 130 formed integrally with the presser foot member 18 to sever the welt at an angle to produce a slanting cut across the welt as previously described. The cutter 50 is attached at its upper end to one arm 60

30 of the cutter actuating lever by means of an angle member 132 which is secured to the upper end of the cutter, and arranged to engage in the slotted end of the lever arm 60. The toggle connection previously described is utilized for maintaining

35 the knife 50 and actuating lever in a raised position comprising the link 72 punched to receive the tapered end of an arm 62 of the lever, and connected to a second toggle link 74 which is pivotally mounted on the presser foot bar 20. The

40 toggle is normally held in its straightened position by means of the small spring 78 to support the knife 50 and actuating lever in their raised position against the pressure of the heavy spring 67. With the modified construction illustrated

45 in Figs. 11 to 15 inclusive, a hand trip lever 134 is secured to the upper link 72 of the toggle to enable the operator conveniently to break the toggle and trip the welt knife into operation at the exact point referred to. It will readily be seen with

50 this construction that while the toggle lever operates as above pointed out, to provide a sure and firm support for the welt cutting knife 50 and spring-pressed actuating lever 60, a gentle pressure on the hand lever 134 will operate instantaneously to break the toggle and sever the welt.

There is also provided with the modified construction, as best illustrated in Fig. 15 of the drawings, a measuring device to enable the operator to conveniently and accurately advance the leading end of the welt to the exact position required for the starting of a new seam. This mechanism

60 comprises a tube 136 which is mounted for a limited sliding movement on a welt guide 138 forming a rearward extension of the guideway 57 on the member 18 and in its rear position extends a predetermined distance beyond the end of the welt guide 138. The movement of the tube 136

65 on the welt guide 138 in each direction is limited by the engagement of a projection 140 on the forward end of the tube with the corresponding slot 142 in the guideway 138. A tension spring 144 connected at one end to the tube, and at its other end to the machine frame, tends to hold the tube normally in a fully extended position.

70 When it is desired to feed the additional welt through the

welt guide preparatory to starting a new seam, the operator grasps simultaneously the rear end of the tube and the welt, and advances the tube and the welt to the forward limit of movement of the tube, as shown in the dotted line position in Fig. 15, thus causing the welt to be advanced a predetermined distance to place the leading end of the welt exactly in the position required. Upon releasing the tube and the welt, the tube will return to its normal full line position as shown 10 in Fig. 15 under the pressure of its spring 144.

The invention having been described, what is claimed is:

1. A sewing machine having, in combination, stitching devices for sewing welt progressively to the outturned upper and sole of a stitch-down shoe positioned on a last, a welt guide, a knife to cut the welt to form a joint with the leading end of the welt, spring means for actuating the knife to cut the welt, toggle members arranged in straightened position to maintain the knife in retracted position against the pressure of the spring, and a trip member adapted when rendered operative to break said toggle to secure a substantially instantaneous cutting of the welt. 25

2. A sewing machine having, in combination, stitching devices for sewing welt progressively to the outturned upper and sole of a stitch-down shoe positioned on a last, a welt guide, a knife to cut the welt to form a joint with the leading end of the welt, means for actuating the knife, and a feeler mechanism comprising a slide movable transversely of the line of feed, a feeler member pivotally mounted thereon actuated by contact with the leading end of the welt to render said means active to cut the welt, and means for adjusting the position of the work engaging portion of the feeler member longitudinally of the line of feed. 30

3. A sewing machine having, in combination, stitching devices for sewing welt progressively to the outturned upper and sole of a stitch-down shoe positioned on a last, a welt guide, a knife to cut the welt to form a joint with the leading end of the welt, a spring-pressed member arranged when rendered operative to actuate the knife, a toggle connection maintained normally in straightened position to hold said member and knife in inoperative position, and a feeler member actuated by contact with the leading end of the welt to break said toggle connection to permit the operation of said member and knife to cut the welt. 40

4. A sewing machine having, in combination, stitching devices for sewing welt progressively to the outturned upper and sole of a stitch-down shoe positioned on a last, a welt guide, a knife to cut the welt to form a joint with the leading end of the welt, means for actuating the knife, a feeler member actuated by contact with the leading end of the welt to render said means active to cut the welt, and means permitting movement of the feeler member laterally of the shoe sole upon contact with the upper. 55

5. A sewing machine having, in combination, stitching devices for sewing welt progressively to the outturned upper and sole of a stitch-down shoe positioned on a last, a welt guide, a knife to cut the welt to form a joint with the leading end of the welt, means for actuating the knife, and a feeler member pivoted to rotate in the line of feed actuated by contact with the leading end of the welt to render said means active to cut the welt, and a hinge connection to permit lateral move- 75

ment of the work engaging portion of said feeler member upon contact with the shoe upper.

6. A sewing machine having, in combination, stitching devices for sewing welt progressively to the outturned upper and sole of a stitch-down shoe positioned on a last, a welt guide; a knife to cut the welt to form a joint with the leading end of the welt, means for actuating the knife, and a feeler mechanism comprising a block laterally supported to slide in bearings in the machine frame, a slide mounted on the block to slide in the direction of movement of the block with relation thereto, a feeler member mounted on the slide arranged upon contact with the leading end of the welt to render said knife actuating means active to cut the welt, and spring means for controlling the position of the slide to maintain a light engaging contact of the feeler with the work.

7. A sewing machine having, in combination, stitching devices for sewing welt progressively to the outturned upper and sole of a stitch-down shoe positioned on a last, a welt guide, a knife to cut the welt to form a joint with the leading end of the welt, spring means for actuating the knife to cut the welt, toggle members arranged in straightened position to maintain the knife in retracted position against the pressure of the spring, and a manually operable member to break said

toggle to secure a substantially instantaneous cutting of the welt.

8. A sewing machine having, in combination, stitching devices for sewing welt progressively to the outturned upper and sole of a stitch-down shoe positioned on a last, a welt guide; a knife to cut the welt to form a joint with the leading end of the welt, spring means tending to move the knife to cut the welt, toggle members arranged in straightened position to maintain the knife in retracted position against the pressure of the spring, and a manually operable trip member formed on one of said toggle members for breaking the toggle to secure a substantially instantaneous cutting of the welt.

9. A sewing machine having, in combination, stitching devices for sewing a welt to the margin of a shoe, a welt guide, a welt cutting knife to sever the welt at the end of an operation on a shoe, and a measuring member mounted on the welt guide for a limited movement in the direction of feed of the welt and arranged to permit the operator to simultaneously grasp the welt and said member to measure the amount of new welt passed through the welt guide by the operator to position the leading end of the welt for a new sewing operation.

FRED ASHWORTH.
